CLAIM

The ornamental design for a sewage pump, as shown and described.

DESCRIPTION

FIG. 1 is a first perspective view of a sewage pump showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 1.

The broken lines shown in the drawings depict portions of the sewage pump that form no part of the claimed design. The dot-dash broken lines in FIG. 1 represent the boundary of the enlarged portion and form no part of the claimed design.
